COMBINED LETTER OPENER, SCALE, AND READING GLASS

Douglas F. Linsley, 23 Main St., Westport, Conn.

Filed Mar. 12, 1959, Ser. No. 54,952

Term of patent 7 years

(Cl. D74—1)

Fig. 1

Fig. 2

Fig. 3

Fig. 4

Fig. 6

Figure 1 is a top plan view of a combined letter opener, scale and reading glass showing my new design; Fig. 2 is a side elevational view thereof; Fig. 3 is a bottom plan view thereof; Fig. 4 is a left end elevational view; Fig. 5 is a right end elevational view; and Fig. 6 is a longitudinal sectional view of the handle portion thereof.

I claim:

The ornamental design for a combined letter opener, scale, and reading glass, as shown.
